UNITED STATES PATENT OFFICE.

CHARLES J. MUEND, OF PHILADELPHIA, PENNSYLVANIA, ASSIGNOR TO HAINES,
JONES & CADBURY INCORPORATED, A CORPORATION OF PENNSYLVANIA.

WASTE VALVE.

Application filed October 23, 1922. Serial No. 596,362.

My invention relates to improvement in waste valves. The object is to provide a simple and efficient valve and cooperating valve seat and also an improved valve actuating mechanism having simple, efficient and convenient means for adjustment, and adjustable friction means for maintaining the valve in any position to which it has been moved by arbitrary actuation.

10 Referring to the drawings, which illustrate merely by way of example suitable means for the embodiment of my invention:—

15 Fig. 1 is a longitudinal vertical section showing some parts in elevation, showing the valve in open position.

Fig. 2 is a similar view showing the valve closed.

20 Fig. 3 is a horizontal section on the lines 3—3 of Fig. 2.

Similar numerals refer to similar parts throughout the several views.

25 The tubular formation 5 is provided with the flange 6 at its upper end, having the valve seat formation 7 on its upper surface, and engaging on its underside with the bevelled wall 8 at the bottom of basin or bowl 9. The tubular formation 5 has the opening 10 communicating with the channel 11, from 30 the overflow 12 of the basin. The lower extension of formation 5 is provided with the exterior thread, as at 12', for cooperating with nut 13. This nut 13 cooperates with washer 14 and gasket 15 for securing 35 a water-tight joint between flange 6 and wall 8, and between gasket 15 and the underside 16 of the basin wall. The threaded portion 12' is of ample extent to permit the tubular formation to be fitted to basins of widely 40 varying dimensions.

The lower threaded end of the tubular formation 5 is in threaded engagement with the housing member or body 17, made watertight by the washer 18. The lower end 19 of body 17 is provided with an interior thread for engagement with the waste pipe 20. The body 18 is also provided, on one side thereof, with the cylindrical formation 21 for the purpose to be explained later.

50 Especial attention is called to the formation of the seat 7, at the top of the tubular formation 5. This seat surface is in the form of a bevel, having the highest line at

its juncture with the inner vertical wall 22 of the tubular formation 5. The valve comprises the plate or member 23, having its underside countersunk, or provided with the downwardly projecting margin or flange 24. Within this countersunk portion, that is on the underside of member 23, is provided the washer 25 having its peripheral margin 26 preferably short of the inner margin of flange 24. This washer 25 is held in place between member or plate 23 and the upper flanged head 27 of the valve spindle formation 28, by means of the screw 29. The valve spindle formation 28, is also provided with the wings 30 for maintaining its proper axial position within the tubular body 5. Spindle formation 28 is also provided at its 70 lower extremity, with the head 31.

The cylinder formation 21 is shown as integral with the chambered body 17 and is in open communication with the interior of chambered body 17. Its axis is horizontal, 75 and it forms a housing for the solid cylindrical formation 32 which has a close but movable fit therein. Into the side of this formation 32 is secured, as by a thread, the arm or rod 33, the free end of which projects into the chambered body 17 and beneath the head 31 of spindle 28. Shaft 34 projects from one end of the member 32 and is preferably integral therewith. The cylinder 21 is closed at one end and is open at the other 80 end and provided with an interior thread, as at 35, for receiving the threaded plug 36 preferably provided with the knurled head 37 for convenient manipulation. This head 36 is centrally apertured for receiving the 85 shaft 34 which projects therethrough. At the closed end of cylinder 21 is provided the spring washer 38 between the end of member 32 and the closed cylinder end wall. Between the plug 36 and the other end of 90 member 32 are provided one or more washers 39 of yielding material such as felt.

The outer extension of shaft 34 is preferably flattened, as at 40, for more effective engagement with set screw 41. An arm or crank member 42 is rigidly secured to the end of shaft 34 by means of the set screw 41. This arm 42 has an extension 43 parallel with the axis of movement of member 32 and is loosely secured to the horizontal 100 rod 44, which is adjustably connected to the

vertically movable actuating rod 45, which has an operating knob 46 at the top and a suitable housing, as at 47, with adjustable means for connecting same to the basin slab, 5 as at 48.

The connecting means between the vertical rod 45 and the horizontal rod 44 comprises the connecting body or member 49 having transverse channels, one for receiving the vertical rod 45 and the other receiving the horizontal rod 44. Vertical adjustment is secured by means of the series of holes 50 in rod 45, adapted to receive cotters 51 above and below member 49 as shown. 10 15 The horizontal adjustment of rod 44 in member 49, is secured by set-screw 52.

The operation is as follows:

As above stated, the long threaded portion 12' permits the tubular formation 5 to be fitted to basin or similar structures having walls differing substantially in thickness. The threaded sleeve 47' forming part of housing 47, in the same way provides for varying dimensions of the supporting slab 48.

The adjustment of rods 44 and 45 in respect to the connecting body 49 and to each other, as above described, brings the actuating knob 46 into proper operating relationship with the cylindrical member 32, so that, by raising or lowering the knob 46, the member 32 is rocked in one direction or the other as required. The arm 33, extending from member 32, beneath the head 31 of spindle 28, serves to raise or lower the spindle 28 and consequently open and close valve 23.

A special feature of the member 32 and its operation, is that said member 32 is interposed between the spring washer 38 and the washers 39 of felt, or other suitable yielding packing. The threaded plug 36 is screwed into the end of the cylinder housing 21, against washers 39 and exerts pressure thereon, which pressure is communicated to the member 32 and the spring washer 38. This pressure may be varied as required, by the simple manipulation of the plug 36; and consequently the friction between the member 32 and the washers at each end thereof, may be brought to any desired degree of efficiency. The result is that when this tension and the resulting friction is properly adjusted, the member 32 40 45 50 55 60 65 may readily be rocked in either direction by simply raising or lowering the knob 46, and thus the valve will be opened or closed as desired, and, in addition to this, the friction exerted on member 32, will maintain the parts securely at any position at which the arbitrary actuation ceases, so that the valve may be opened or closed or partly opened or partly closed, and in whatever position left, in said arbitrary actuation, the valve will remain, until again positively actuated.

This is considered a distinct advantage in the actuating mechanism of valves of this class.

Another feature of the construction herein described, is the valve seat formation and construction. The upper surface of the flanged tubular formation, which forms the seat proper, is bevelled; that is, it is inclined downwardly from the inner margin thereof to the outer margin, so that this annular bevelled seat has its highest line at its junction with the inner vertical wall 22 of the vertical tubular formation 5. The said outer margin has a diameter at least equal to the diameter of the outer margin of the valve. 70 75 80 85 The washer 25 of the valve element, which is flat and formed of rubber or other yielding material, cooperates with this bevelled seat with a preliminary line engagement and causes an efficient closure, since the slightly raised ridge at the inner margin of the valve seat, tends to sink very slightly into the yielding body of the washer, but as it sinks, the area of engagement between the valve and its seat is very greatly increased, and thus a liquid-tight closure is effected with a minimum of pressure. 90

The parts are simple in construction, easy to assemble and have little wear or other tendency to get out of order. 95

What I claim is:—

1. In a waste valve mechanism, the combination of a valve, a valve spindle, a housing for the lower end of the spindle, a cylindrical bearing associated with the housing, a cylindrical body seated in said bearing, a spring washer interposed between one end of the cylindrical body and the housing, a fibrous body engaging the opposite end of the cylindrical body, serving both as a packing and as a friction element, a knurled threaded plug as adjustable means for exerting pressure upon the fibrous body and the cylindrical body, means for actuating the cylindrical body and means for communicating movement from the cylindrical body to the spindle. 100 105 110 115

2. In a waste valve mechanism, the combination of a valve, a valve spindle, a housing for the lower end of the spindle, a cylindrical bearing associated with the housing, a cylindrical body seated in said bearing having a shaft projecting therefrom, a spring washer interposed between the end of the cylindrical body and the housing, means for communicating movement from the cylindrical body to the spindle, and means for actuating the cylindrical body including a crank arm connected to the shaft and having an extension corresponding to the extension of the cylindrical bearing and parallel to the axis of the cylinder, a horizontal rod having swivel connection with the crank arm, a vertical rod, and a connecting element having adjustable engage- 120 125 130

ment with both the horizontal rod and the vertical rod.

3. In a waste valve mechanism, the combination of a valve seat, a valve, a valve spindle and spindle actuating means, the valve seat surrounding the top of a vertically extending tubular formation, and having its engaging surface of gradual inclination downwardly from the inner vertical

wall of the tubular formation, and the valve 10 comprising a flat top plate having a downwardly extending peripheral flange, and a body of yielding material secured to the underside of the plate and within the flange and having a flat under surface for engaging the valve seat. 15

CHAS. J. MUEND.
